EDWARD E. ROBERTS, OF HARTFORD, CONNECTICUT.

FUSE.

1,077,369.

Specification of Letters Patent.

Patented Nov. 4, 1913.

Application filed December 29, 1911. Serial No. 668,354.

To all whom it may concern:

Be it known that I, EDWARD E. ROBERTS, a citizen of the United States, and a resident of Hartford, in the county of Hartford and 5 State of Connecticut, have invented a new and Improved Fuse, of which the following is a full, clear, and exact description.

This invention relates to inclosed electric safety fuses. Fuses of this character have 10 one or more fusible links inclosed in an insulating casing and surrounded by a granular, pulverized or flocculent non-conducting material which is provided to diffuse and retard the flow of the hot gases that are 15 evolved when the fusible link or links are changed from a solid state to a gaseous condition, and thus while allowing the escape of the gases so cooling them that the possibility of explosion is eliminated and the out- 20 flow of flame and molten metal, which would be liable to cause disastrous conflagration, is prevented.

The object of this invention is to so construct a fuse of this nature that many restricted paths are provided for the hot gases evolved by the fusion of the metal whereby the gases will be dispersed throughout the filling material and the arc quickly quenched, and yet at the same time to provide a relatively free passage for the outflow of the cooled gases and also the air that is between the particles of filling material and that is expelled by the gases at the instant the fuse blows. To accomplish this 35 end the interior of the casing which incloses one or more fusible links is divided into two or more compartments. In the compartment or compartments containing a fusible link is a granular non-conducting material of relatively fine particles for the purpose of absorbing and thoroughly diffusing and cooling the gases evolved by the volatilization of the metal and smothering the arc. In the other compartment or compartments 40 is a granular non-conducting material in a relatively coarser state, which provides an easier path for the escape of the gases and also the air between the particles which is expelled by the gases, and thus insuring a rapid reduction of internal pressure which 45 will eliminate the danger of explosion and cause a quick and safe opening of the circuit.

Figure 1 of the accompanying drawings 50 shows a central longitudinal section of a multiple link fuse which embodies this in- vention. Fig. 2 shows a transverse section of the same on the plane indicated by the dotted line 2-2 on Fig. 1. Fig. 3 shows a central longitudinal section of a single flat strip link fuse which embodies the invention. Fig. 4 shows a transverse section of the single link fuse on the plane indicated by the dotted line 4-4 on Fig. 3. Fig. 5 shows a central longitudinal section of a 55 modification of a single link fuse which embodies the invention. Fig. 6 shows a transverse section of the fuse shown in Fig. 5 on the plane indicated by the dotted line 6-6. Fig. 7 is a fragmentary view showing how 60 openings may be made in an inner tube.

The fuses illustrated are of the ferrule contact type, but the invention is not limited to fuses of this type. In the form first shown the fuse has a tubular casing 10 which 65 is preferably made of vulcanized fiber. The ends of the casing are closed by end caps 11 which may be made of brass or any other suitable conducting material. In this casing four round fusible links 14 are shown, 70 although the invention is not limited to the number of or the shape of the links. These links at their ends are connected with the internal terminals 15 which are commonly 75 made of copper and are secured to the end 80 caps so as to form a close electrical connection therewith. In this form there is an inner tube 12 which can be made of vulcanized fiber or any other suitable electrical insulating material. The inner tube has 85 openings 13 through its side near the middle. Through the end caps at the ends of the inner tube it is desirable to have vents 17.

The inner tube is filled with an electrical non-conducting material 18 of relatively 90 coarse grains. This coarse material is permitted to flow through the openings in the tube and to surround the middle of the fusible links. The remainder of the space 95 between the inner and outer tubes and around the fusible links and inner terminals is filled with an electrical non-conducting material of relatively finer grains. As a result of this construction the fusible links tend to rupture first at the middle 100 owing to the fact that the coarse material does not conduct away the heat as readily as the fine material, and because of the larger air spaces and easier course for the molten metal, the gases and air through the 105 coarse material, the gas pressure will be reduced at the middle when the metal vapor-

2
izes. For these reasons the fuse opens quickly and quietly without danger of bursting or the expulsion of flame and molten metal.

5 In the second form shown there is but a single flat strip fusible link 14^a provided with the usual calibration opening 14^e. In this form the outer tubular casing 10^a is made of insulating tubing and provided 10 with metallic end caps 11. The interior of this casing is separated into two chambers by the inner insulating tube 12^a. The inner tube has openings 13^a through its side near the middle, which provide communication 15 from one chamber to the other. It is desirable to vent the casing outside of the inner tube by making openings 17^b through the end caps. Between the inner and outer tubes and in the openings through the inner 20 tube is filled the relatively coarse non-conducting granular material 18^a, and in the remaining space in the inner tube about the fusible link and inner terminals a relatively finer non-conducting granular material 19 25 is filled. In this form of fuse the coarse material provides a relatively easy path for the gases developed when the element fuses so as to relieve the tension while the finer material absorbs the remaining gases and 30 smothers the arc.

In Fig. 5 the fusible link 14^b is shown as a single round wire electrically connected with the caps 11^b which close the ends of the outer tubular insulating casing 10^b. Extending from end cap to end cap in this 35 form of fuse are two insulating tubes 12^b which have openings 13^b through their sides near the middle. In this case vent holes 17^b are made through the end caps opposite the 40 ends of the inner tubes 12^b. Non-conducting material 18^b of relatively coarse grain is filled into the inner tubes 12^b and through the openings and about the middle of the fusible link. Disposed in the remaining 45 space about the link and inner tubes is non-conducting material 19^b in a relatively fine state. In this case a comparatively easy path is provided for the cooled gases through the coarse material in the inner 50 tubes and out through the vent openings at the ends, leaving the finer material to absorb the molten metal, and quench the arc.

In a fuse constructed according to this invention the relatively coarse granular 55 non-conducting material provides a comparatively easy path for the hot gases and molten metal when the link or links first melt and also an easy path for the air which is driven out by the generated gases. 60 The path, however, about the coarse particles is sufficiently tortuous to cool the gases and absorb the molten metal so that nothing dangerous escapes from the casing when the fuse blows. As the links melt back, the 65 finer filling material provides more of an

obstruction to the flow of gas and molten metal and there are more spaces for absorbing the gases, and as the pressure has been relieved by the first flow of the gases and air out through the coarse material, the following gases are readily absorbed in the spaces between the grains of the finer material, and if not completely absorbed they are so cooled by passing through the finer material that they will flow out through the coarser material without dangerous effect. A fuse constructed in this manner, whether of the single link or multiple link type arranged in a casing that is divided in the interior into two or more chambers, one of which is filled with material that provides a relatively easy path for the gases, will open quickly at the desired time without danger of explosion or discharging flames or molten metal to the atmosphere.

The invention claimed is:

1. In a fuse, a casing having two passages with an opening from one to the other, a fusible member in one of the passages, a non-conducting granular filling in the last-mentioned passage, and a coarser non-conducting granular filling in the other passage, the coarser filling extending through said opening to the fusible member.

2. In a fuse, a casing having two passages with an opening from one to the other, a fusible member in one of the passages, a non-conducting granular filling in the last-mentioned passage, and a coarser non-conducting granular filling in the other passage.

3. In a fuse, a casing having two passages with an opening from one to the other, a fusible member in one of the passages, a non-conducting granular filling in the last-mentioned passage, and a coarser non-conducting granular filling in the other passage, the passage containing the coarser filling being vented to the atmosphere.

4. In a fuse, a casing having two passages with an opening from one to the other, and a fusible member in one of the passages, said passages being respectively filled with granular non-conducting material of different degrees of granulation.

5. A fuse having a casing divided in the interior into a plural number of communicating chambers, a fusible member in one of the chambers, a non-conducting granular material about the fusible member, and a non-conducting granular material of coarser granulation which will permit the easier escape of the gas in the other chamber.

6. A fuse having a casing, a fusible element, and non-conducting granular material filling the casing about the fusible element, said non-conducting material having grains of different sizes, the finer surrounding the fusible element near its ends and the coarser surrounding the fusible element near its middle and providing an easier path for the

flow of the gases developed on the melting of the fusible member, than through the finer material.

7. A fuse having a vented casing, a fusible member therein, a non-conducting granular material disposed about the fusible member, and a relatively coarser non-conducting granular material surrounding the middle of the fusible element and leading to the vents in the casing, said coarser material serving as a means of escape for the gases developed on the melting of the fusible member.

8. A fuse having two longitudinal passages with an opening intermediate the ends providing communication from one passage to the other, a non-conducting granular material filled in one of the passages, a fusible member disposed in the said passage, and a relatively coarser non-conducting granular material filled in the other passage and extending through said opening to the fusible member.

9. In a fuse, two tubes, one disposed within the other, there being an opening in the inner tube communicating with the space

between the inner and outer tubes, non-conducting granular material filling the tubes, the filling material on one side of the wall of the inner tube being coarser than that on the other side, and a fusible member extending through the finer filling.

10. In a fuse, two tubes, one disposed within the other, there being an opening in the inner tube affording communication from the inner tube to the space between the inner and outer tubes, non-conducting granular material filling the tubes, the filling on one side of the wall of the inner tube being coarser than that on the other side, a fusible member extending through the finer filling, and heads closing the ends of the outer tube, said heads having vents communicating with the coarser filling material.

In testimony whereof I have signed my name to this specification in the presence of two subscribing witnesses.

EDWARD E. ROBERTS.
